(57) **CLAIM**

The ornamental design for a digital photo frame, as shown and described.

DESCRIPTION

FIG. 1 is a front, right side, top perspective view of a digital photo frame showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the encircled region 9 shown in FIG. 3; and,

FIG. 10 is an enlarged view of the encircled region 10 shown in FIG. 4.

The broken lines in the figures are for the purpose of illustrating portions of the digital photo frame, which form no part of the claimed design.

1 Claim, 10 Drawing Sheets
